CLAIM

The ornamental design of an EEG measuring device, as shown and described.

DESCRIPTION

FIG. 1 is a perspective view of an EEG measuring device showing the claimed design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The even dashed broken lines shown in the drawings represent portions of the EEG measuring device, that form no part of the claimed design.

1 Claim, 7 Drawing Sheets
